Primary Examiner — Vy N Koenig*Assistant Examiner* — Benjamin D. Wannemacher(74) *Attorney, Agent, or Firm* — Daniel M. Cohn;
Howard M. Cohn(57) **CLAIM**

The ornamental design for a plant cover, as shown and described.

DESCRIPTION

FIG. 1 is a perspective view of a plant cover showing my new design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is a bottom plan view of a plant cover as shown. The broken lines are for the purpose of illustrating portions of the plant cover that form no part of the claimed design.

1 Claim, 7 Drawing Sheets(56)
